W. E. HICKS, OF McMECHEN, WEST VIRGINIA.

PHOTOGRAPHIC-PRINT-EXPOSURE APPARATUS.

1,185,866.

Specification of Letters Patent.

Patented June 6, 1916.

Application filed August 11, 1915. Serial No. 45,008.

To all whom it may concern:

Be it known that I, LAWRENCE A. BELL, a citizen of the United States of America, and resident of McMechen, county of Marshall, and State of West Virginia, have invented certain new and useful Improvements in Photographic-Print-Exposure Apparatus, of which the following is a specification.

10 This invention relates broadly to photograph developing apparatus, and more specifically to a device for timing the exposure of photographic prints.

15 The primary object of the invention is to provide an apparatus for photographic printing having means for accurately timing the exposure of prints to the action of the printing rays of light.

20 A further object is to provide a device of the character described embodying means whereby, when the door of the printing compartment is closed, the lamps from which the printing rays emanate are automatically lighted. And a still further object is to provide, in a device of the character mentioned, adjustable means automatically set in operation by the closing of the door of the printing compartment whereby said door is opened at the end of 25 an interval of predetermined duration, accomplishing the extinguishment of the lights.

With these and other objects in view, the invention resides in the features of construction, arrangement of parts and combinations of elements which will hereinafter be exemplified, reference being herein had to the accompanying drawings, forming a part of this specification, in which—

30 Figure 1 is a front elevation of the invention, showing the doors partially open; Fig. 2 is a diagrammatic view of the electric wiring, showing the lamps lighted; Fig. 3 is a similar view, showing the lamps out; Fig. 4 is an enlarged partial vertical section, showing the timing mechanism in rear elevation; Fig. 5 is a section on line 5—5, Fig. 4; Fig. 6 is a partial top plan view, showing a part of the door-control mechanism; Figs. 7 and 8 are horizontal sections taken respectively on lines 7—7 and 8—8, Fig. 4; Fig. 9 is a section on line 9—9, Fig. 6; and Fig. 10 is a section on the line 10—10, Fig. 8.

35 Referring to said drawings, in which like

designating characters distinguish like parts throughout the several views—1 indicates a casing containing one or more printing compartments, two such compartments 2 and 3 being shown in the drawings. Also 60 provided within said casing is a compartment 4 in which is located the larger portion of the timing mechanism. Access to the printing compartments 2 and 3 is had through hinged doors 5 and 6 respectively, 65 said doors opening through the front wall of said casing. Each compartment is provided with a red lamp 7 and one or more white or clear glass lamps 8, the electric wiring for said lamps being such that the 70 lamps 7 remain lighted continuously and the uncolored lamps 8 are lighted only so long as the doors remain closed.

Suitably mounted in the lower part of compartment 4 are bearings 9 in which is 75 journaled a horizontal drive-shaft 10 which carries thereon a pulley 11 designed to be connected by belt to a motor or other source of power (not shown). Fixed on said shaft at a suitable point is a worm gear 13 disposed in driving relation to a spur gear 12 carried by a vertically disposed feed screw 14 having threads with a predetermined pitch. Said feed-screw has its opposite ends journaled in suitable bearing members 80 15 and 16 provided, respectively, at the upper and lower ends of said compartment 4, and preferably rotates on ball bearings provided in said members.

Rotatably mounted in a suitable supporting bracket, as 17, located in the lower end of compartment 4, are the lower ends of two vertically disposed rods 18 and 18' the upper ends of which are extended through and are rotatable in the top of the 90 casing 1. Fixed on said rod 18 adjacent to its upper and lower ends, respectively, are arms 19 and 20 in which are fixed the opposite ends of a vertical rod 21; and fixed on the rod 18' are two arms 19' and 20', similar to arms 19 and 20, which carry a vertical rod 21'. Vertically slidable on the rod 18 is a bracket 22 having an arm 22^a slidable upon rod 18; and a similar bracket 22' is slidably mounted on rods 18' and 21'. 95 Seated respectively upon the arms 22^a and 22^b of said brackets are annularly grooved cylinders 23 and 23' the grooves of which correspond in width with the threads provided on the feed screw 14. Said cylinders 100 105 110

23 and 23' are rotatably mounted on said rods 21 and 21', respectively, and normally rest upon their respective seating arms 22^a and 22^b, and the latter are normally held 5 swung outward to positions wherein said cylinders are out of engagement with said feed screw. When, however, one of the rotatable rods, as 18, is slightly rotated inward, the cylinder 23 will be thrust into 10 engagement with the rotating feed screw and will thereby be caused to travel upward on the rod 21.

Fixed upon the upper projecting ends of the rods 18 and 18', respectively, are the 15 ends of levers 24 and 24'. Pivottally connected to the opposite end of lever 24 is a rod 25 which has its opposite end pivoted to the free end of a lever 26 carried by the upper end of a vertically disposed rotary 20 rod 27 which projects upward through the top of the casing 1. The body portion of said rod 27 lies within compartment 3 adjacent to the wall 28 which separates said compartment from compartment 4, and is 25 rotatably supported on or in one or more brackets 29. Fixed on the lower end of said rod 27 is one end of a lever 30 to the opposite end of which is pivottally connected one 30 end of a pin 31 which is movable horizontally through a vertically disposed strip or cleat 32 against which the front edge portion of the door 6 is adapted to seat when the latter occupies closed position. A spiral spring 33 disposed in encircling relation to the rod 25 has one end seated against a shoulder 34 formed on said rod and its other end seated against an upright lug 35 through which said rod is movable, said lug being rigidly mounted upon the top of 35 40 the casing. Said spring serves to normally maintain said rod 25 in a retracted position, maintaining the cylinder 23, through the intermediate mechanism, out of operative engagement with the feed screw, and also 45 maintaining the pin 31 projected outward beyond the face of the cleat 32. When, however, the door 6 is closed, the pin 31 is thereby thrust inward against the tension of the spring 33, and, through the intermediate 50 mechanism described, the cylinder 23 is thrust into engagement with the rotating feed screw. Prior to reaching the limit of its upward travel, the upper end of the cylinder 23 engages the end of one arm of a 55 bell-crank lever 36 the angular portion of which is mounted upon a suitably located pivot pin 37 and which has its other arm projected upward through a suitable slot 38 provided in the top of the casing. The 60 upper end of the upright arm of said bell-crank has pivottally connected thereto one end of a horizontally disposed angular rod or bar 39 the opposite end of which is pivottally connected to one end of a lever 40 65 which is fixed upon the upper projecting

end of a vertical rod 41 which is rotatably mounted, as in the top of the casing 1 and in a bracket 42 carried on the inner face of the cleat 32. Fixed upon the lower end of said rod 41 is a latch 43 which extends outward through and is laterally movable in an opening 44 provided in the cleat 32, said latch being adapted to assume interlocking engagement with a suitable catch, as the edge of a plate 45, carried by the door 6 for 70 securing the latter in closed position. A spiral spring 46 disposed in encircling relation to the bar 39 between a shoulder 47 formed on the latter and a bracket 48 through which said bar is movable serves 75 to yieldingly maintain the latch 43 in a position for engaging the catch 45 of the door, and also normally holds the bell crank 36 in a rearwardly thrust position wherein its lowermost arm occupies a downwardly inclined position in the path of movement of 80 the cylinder 23.

From the foregoing it will be apparent that, upon closing the door 6, the bell-crank 36 will occupy the position just mentioned; 90 further, the pin 31 will thereby be pressed inward, and, through the intermediate mechanism described, the cylinder 23 will be thrust laterally into engagement with the constantly rotated feed screw 14 whereby it 95 will be caused to travel upward. When said cylinder engages the depending arm of the bell-crank 36, the latter will thereby be gradually elevated until, through the intermediate mechanism described, the latch 43 100 will be laterally withdrawn from interlocking engagement with the catch of the door 6, whereupon the latter will spring open, actuated by the pin 31 which, due to the tension of spring 33, normally occupies an outwardly thrust position.

The closing and opening of the door 6 respectively act to close and open an electric lamp circuit passing through the lamps 8 of compartment 3. Said lamp circuit is normally open, having its opposite terminals 49 and 50 connected respectively to a fixed contact 51 provided within the cleat 32 and a movable contact 62, the latter being yieldingly disposed in a position where it will be 110 engaged by the door and thereby pressed inward into engagement with the fixed contact 50 when said door is closed, thus effecting the lighting of said lamps. The wiring 115 for the lamps is such that the circuit through the clear glass lamps 8 is normally open and the circuit through the colored lamp 7 is permanently closed, as shown in Figs. 2 and 3.

The lighting of compartment 2 is controlled in a manner identical with that described with respect to compartment 3, the mechanisms intermediate the door 5 and the cylinder 23' being substantially identical with those between the door 6 and the cylinder 23; and in the drawings, the parts of 125 130

the former corresponding to parts of the latter are designated by corresponding characters bearing a prime exponent.

As is apparent, the duration of time during which photographic prints placed in the compartments 2 or 3 are subjected to the printing rays of the lamps 8 is regulated by adjustment of the travel of the cylinders. In other words, the rate of rotation of the feed screw 14 being constant, the cylinders will travel a definite distance in a given time; and, therefore, the support 22 may be preliminarily positioned on rods 18 and 21 so that it supports the cylinder 23 at a point remote from the door-opening position of the depending arm of the bell-crank 36 a distance which will be traversed by said cylinder in a length of time corresponding to the duration of the exposure to which it is desired the prints in compartment 3 shall be subjected. While the adjustment of the support 22 may be accomplished in any appropriate way, the means employed in the present embodiment comprises a flexible tape 52 which is wound on a reel 53 revolubly mounted on a horizontally disposed shaft 54 which is suitably supported, as in oppositely disposed frame members 55. The support 22 is suspended on the free end of said tape. Fixed on said reel is a spur gear 56 in mesh with a worm-gear 57 which is fixed on a shaft 58 journaled in suitably located bearings 59. The front end of said shaft 58 projects outward through the front wall of the casing 1 and has formed thereon or attached thereto a hand crank 60 by means of which it may be rotated for effecting the raising or lowering of said support 22.

The tape 50 is graduated or has printed thereon suitably spaced numbers or other suitable indicia, as shown most clearly in Fig. 8, whereby the adjustment may be facilitated, and a sight glass 61 provided in the casing directly in front of the reel 53 affords means for viewing said indicia. Assuming, for example, that it is desired that the prints, cards, or the like to be printed within compartment 3 shall be exposed to the printing rays of the lamps 8 for a period of forty-five seconds, the reel 53 is rotated until the number "45" carried by the tape 52 is exposed to view through the sight glass. Said number "45" being so located on said tape that 45 seconds travel of the cylinder 23 will be required to effect the opening of the door 6 and the resultant breaking of the lamp circuit, the printing frame containing or bearing the prints is placed within compartment 3 and the door 6 is closed. The circuit through the lamps is thereby closed, lighting the lamps, and simultaneously the cylinder 23 is swung into engagement with feed screw 14 and immediately begins its ascent. At the expiration of 45 seconds, the bell-crank 36 will be moved

to a position wherein, through the intermediate mechanism, the door 6 will be released, whereupon the lamp circuit is broken in the manner hereinbefore described.

The means employed for adjustment of support 22' for regulating the exposure of prints in compartment 2 is substantially similar in all respects to that described in connection with the adjustment of support 22, and in the drawings the parts of the former corresponding to parts of the latter are designated by corresponding characters bearing a prime exponent.

What is claimed is—

1. A photographic print-exposing apparatus, comprising a printing compartment, electric lamps in said compartment, a normally open electric circuit in which said lamps are included, a door opening into said compartment, means actuated by closing of said door for closing the lamp circuit, a constantly driven element, and adjustable door-opening means normally disengaged from said element, said door-opening means being moved into operative relation to said element by the closing of said door and being adapted to effect the opening of said door at the expiration of a predetermined interval.

2. A photographic print-exposing apparatus, comprising a printing compartment, electric lamps in said compartment, a normally open electric circuit in which said lamps are included, a door opening into said compartment, means actuated by closing of said door for closing the lamp circuit, a latch for holding said door in closed position, trip mechanism associated with said latch, a constantly driven element, a member adapted to be driven by said element into tripping relation to said trip mechanism whereby said latch is caused to release said door, said member being normally held in inoperative position with respect to said element and being moved into operative relation thereto by closing of said door, and means for so adjusting said member that a predetermined interval will intervene between the closing and opening of the door.

3. A photographic print-exposing apparatus, comprising a printing compartment, electric lamps in said compartment, a normally open electric circuit in which said lamps are included, a door opening into said compartment, means actuated by closing of said door for closing the lamp circuit, a latch for holding said door in closed position, trip mechanism associated with said latch, a constantly driven element, a member adapted to be driven by said element into tripping relation to said trip mechanism whereby said latch is caused to release said door, said member being normally held in inoperative position with respect to said element and being moved into operative re-

lation thereto by closing of said door, and means for so adjusting the initial position of said member with respect to the tripping position thereof that its travel to said tripping position will occupy a predetermined interval.

4. A photographic print-exposing apparatus, comprising a printing compartment, electric lamps in said compartment, a normally open electric circuit in which said lamps are included, a door opening into said compartment, means actuated by closing of said door for closing the lamp circuit, a latch for holding said door in closed position, a constantly driven element, a member adapted to be driven by said element, a lever disposed in the path of travel of said member and adapted to be moved by the latter, means interposed between said lever and said latch whereby the latter is released permitting said door to open when said lever is moved by said member, means for adjusting the initial position of said member, and means normally holding said member in inoperative position, the last mentioned means being actuated by closing of said door to move said member into operative relation to said element.

5. A photographic print-exposing apparatus, comprising a printing compartment, electric lamps in said compartment, a normally open electric circuit in which said lamps are included, a door opening into said compartment, means actuated by closing of said door for closing the lamp circuit, a latch for holding said door in closed position, a constantly rotated vertically disposed feed screw, a grooved cylinder adapted to be elevated by said screw, a lever disposed in the path of travel of said cylinder and adapted to be swung by the latter at a predetermined point in its travel, means interposed between said lever and said latch

whereby the latter is released permitting the door to open when the former is actuated by said cylinder, and means normally holding said cylinder out of engagement with said screw, the last-mentioned means being actuated by closing of said door to move said cylinder into operative relation to said screw.

6. A photographic print-exposing apparatus, comprising a printing compartment, electric lamps in said compartment, a normally open electric circuit in which said lamps are included, a door opening into said compartment, means actuated by closing of said door for closing the lamp circuit, a latch for holding said door in closed position, a constantly rotated vertically disposed feed screw, a grooved cylinder adapted to be elevated by said screw, a lever disposed in the path of travel of said cylinder and adapted to be swung by the latter at a predetermined point in its travel, means interposed between said lever and said latch whereby the latter is released permitting the door to open when the former is actuated by said cylinder, means normally holding said cylinder out of engagement with said screw, the last-mentioned means being actuated by closing of said door to move said cylinder into operative relation to said screw, the last-mentioned means being actuated by closing of said door to move said cylinder into operative relation to said screw, and means for initially adjusting said cylinder with respect to said screw whereby a period of travel of predetermined duration will occur between the engagement of the cylinder with the screw and the actuation of said lever.

In testimony whereof, I affix my signature in presence of two subscribing witnesses.

LAWRENCE A. BELL.
